UNITED STATES PATENT OFFICE.

SETH A. CRONE, OF EAST ORANGE, NEW JERSEY.

RAILWAY BRAKE-BEAM.

No. 911,867.

Specification of Letters Patent.

Patented Feb. 9, 1909.

Application filed November 14, 1908. Serial No. 462,574.

To all whom it may concern:

Be it known that I, SETH A. CRONE, a citizen of the United States, and a resident of East Orange, in the county of Essex and 5 State of New Jersey, have invented certain new and useful Improvements in Railway Brake-Beams, of which the following is a specification.

The invention relates to improvements in 10 railway brake-beams, and consists in the novel features hereinafter described, and particularly pointed out in the claims.

My invention pertains to truss-beams and resides more particularly in a novel strut 15 and means for securing the same to the compression member, as hereinafter explained.

The invention will be fully understood from the detailed description hereinafter presented, reference being had to the accompanying drawings, in which:

Figure 1 is a top view of the middle portion of a railway brake-beam constructed in accordance with and embodying the invention, and Fig. 2 is a side view of the strut, 25 with the truss rod shown in central transverse section and the compression member in transverse section on the dotted line 2—2 of Fig. 1.

In the drawings, 10 designates the compression member, 11 the truss-rod and 12 the strut, the truss-rod being of customary character and secured at its ends to the ends of the compression member, as usual in truss-beams. The compression member 10 35 is formed of a rolled flanged section and is preferably of T-shape in cross - section, as shown.

The strut 12 is of cast metal and at one end engages the middle portion or bend of 40 the truss-rod in a customary manner, while at its other end said strut engages the compression member and is secured thereto by means of upper and lower specially constructed corresponding clamps 14, 14 and a 45 vertical rivet or bolt 15. The outer end of the strut 12 is slotted or recessed, as at 16, to receive the web 17 of the compression member 10, and the extreme end surface of the strut is oppositely tapered, as denoted by 50 dotted lines 18 in Fig. 1, so as to ride against and firmly engage the flange portions of said member 10. The base of the recess 16 in the strut is also curved, as shown by dotted lines in Fig. 1, so as to facilitate any necessary angular movement of the strut to the

straight position shown in Fig. 1 in applying it to position between the compression member and truss-rod. The outer end of the strut 12 is formed on its upper and lower sides with shoulders 19 and at the ends of 60 said shoulders with integral outwardly projecting lugs 20 which are of angular formation and therefore project from the upper and lower sides of the strut and also in a direction from the shoulders 19: 65

The upper and lower clamps 14 may be either of forged metal or malleable castings and they have inwardly directed ends 21 to engage the edges of the flange of the compression member 10 and the shoulders 19 of 70 the strut. The clamps 14 at the corners of their inner ends are recessed, as at 22, to fit partly around and between the lugs 20, as shown in Fig. 1, whereby the correct application of the clamps is facilitated and the rivet 75 or bolt holes therein become centered with the like holes through the strut and web of the compression member. I do not limit my invention to the recesses 22 and lugs 20 but these features are of importance and perform a special duty. In applying the strut 12 to the other parts of the beam, the usual 80 end nuts securing the ends of the truss-rod may be loosened and the strut introduced 85 between the truss-rod and compression member, after which the upper and lower clamps 14 are applied to position and secured by means of the bolt or rivet 15 which extends through both clamps, the end of the strut and the web of the compression member. 90 In instances where it may not be desired or possible to loosen the ends of the truss-rod preparatory to applying the strut to position, I will first place the strut between the compression member and truss- 95 rod in an angular position with one end of the strut on the middle bend of said rod and the other end of the strut against the compression member, with the web 17 of the latter in the recess 16, and then force the outer end 100 of the strut along the compression member until the strut attains its straight position, whereupon I will apply the clamps 14 and rivet 15 in the manner hereinbefore explained. 105

The clamps 14 afford, with the bolt or rivet 15, very desirable and efficient means for securing the strut and compression member together, said rivet closely binding the clamps against the upper and lower adjacent 110

portions of the strut and compression member and the ends 21 of said clamps aiding in preventing the separation of said strut and member. The clamps 14 are exactly alike 5 and either may be applied to either the upper or lower side of the strut and compression member. The clamps 14 are comparatively inexpensive of manufacture and one advantage they possess is that they may be 10 quickly applied to position with the exercise of the least skill and exertion on the part of the mechanic. The clamps 14 are independent of each other and any injury to one clamp will not affect the other clamp and 15 hence the cost of repairs with respect to the clamps is reduced to the minimum. When the clamps possess the recesses 22 and the strut the lugs 20 it is substantially impossible to apply the clamps except directly 20 and immediately in a correct position with the holes for the rivet 15 in proper line to receive said rivet, said recesses and lugs serving to guide the clamps at once to their proper final positions.

25 What I claim as my invention and desire to secure by Letters-Patent, is:

1. A brake-beam comprising a compression member, a truss-rod and a strut, said compression member being a rolled section 30 and the end of said strut engaging said member and being seated on a horizontal portion of the same and having shoulders on its upper and lower sides, combined with independent clamps applied to the upper and lower 35 sides of the adjacent portions of said strut and compression member and having inturned ends which engage said shoulders and the edge portions of said compression member, and a bolt or rivet extending vertically 40 through said clamps, strut and compression member; substantially as set forth.

2. A brake-beam comprising a compression member, a truss-rod and a strut, said compression member being a rolled section 45 and the end of said strut engaging said member and being seated on a horizontal portion of the same and having shoulders on its upper and lower sides, combined with independent clamps applied to the upper and 50 lower sides of the adjacent portions of said

strut and compression member and having inturned ends which engage said shoulders and the edge portion of said compression member, and a bolt or rivet extending vertically through said clamps, strut and compression member, said strut having projecting lugs at the ends of said shoulders and said clamps having recesses at the corners of their inner ends to receive said lugs; substantially as set forth. 55

3. A brake-beam comprising a compression member which is of T-shape in cross-section, a truss-rod and a strut, the end of the strut being recessed to pass on the web of the compression member and formed with shoulders on its upper and lower sides, combined with independent clamps applied to the upper and lower sides of the adjacent portions of said strut and compression member and having inturned ends which engage said shoulders and the edge portions of said compression member, and a bolt or rivet extending vertically through said clamps, strut and web; substantially as set forth. 60

4. A brake-beam comprising a compression member which is of T-shape in cross-section, a truss-rod and a strut, the end of the strut being recessed to pass on the web of the compression member and formed with shoulders on its upper and lower sides, combined with independent clamps applied to the upper and lower sides of the adjacent portions of said strut and compression member and having inturned ends which engage said shoulders and the edge portions of said compression member, and a bolt or rivet extending vertically through said clamps, strut and web, said strut having projecting lugs at the ends of said shoulders and said clamps having recesses at the corners of their inner ends to receive said lugs; substantially as set forth. 75

Signed at New York city, in the county of New York, and State of New York, this 13th day of November A. D. 1908.

SETH A. CRONE.
